UNITED STATES PATENT OFFICE.

JOHN JIRASEK, OF DETROIT, MICHIGAN.

HOT-WATER VEST.

Application filed May 10, 1926. Serial No. 107,852.

The object of my invention is to produce a flexible hot water jacket, suitable for use in the sick room, and especially of patients confined to the bed, for inclosing the shoulders and upper part of the body therein, providing means for uniformly applying artificial heat to the body.

Another object is to produce a hot water jacket, or vest that is capable of being spread out in a single flat sheet, or folded into a jacket inclosure about the body of a patient.

A further object is to provide a hot water vest made in separate sections, all so arranged that each section may be filled separately and independently from the others, providing means for changing the water in the vest by removing only one section from the body of the patient at a time.

It is well known, and has long been practiced by physicians to apply artificial heat to the body of patients, for raising the temperature of the body, or for removing inflammation therefrom, usually by means of applying thereto heated clothes, or pads, or by the use of small hot water bottles now commonly known and used. It has been found that in cases of pneumonia, or similar ailments, application of artificial heat to all parts of the body surrounding the lungs, simultaneously, is of great benefit in relieving the causes of the ailment, and that a jacket, or vest, having a series of hot water compartments which will surround and inclose the shoulders and upper part of the body, and especially the vital organs, will readily relieve pain from such inflammation and greatly assist in healing the affected parts.

In general, my device comprises several hollow, flexible waterproof sections, so arranged and combined as to be capable of being spread out in a flat sheet member, formed and designed by outer contour lines so it may readily be folded about the body and shoulders of a patient with its edges fitting and engaging together, forming a closed vest for the shoulders and upper part of the body, capable of being entirely filled with hot water, and practically inclosing the body therein. The jacket is provided with means for filling the several sections with water, separately, and with means for attaching the ends together, forming a complete jacket enclosure.

I attain these results by the construction and arrangements of parts more fully hereinafter set forth.

Similar parts on all drawings are marked by similar numerals or letters.

Fig. 1, is a front view of my hot water vest, as would appear when worn by a patient.

Fig. 2, is a side view of the vest showing the relative position of the front and back sections.

Fig. 3, is a top view of the vest showing the relative position of all of the attached sections when the vest is folded together, ready for use.

Fig. 4 is a bottom view of the folded vest, illustrating means for attaching the several sections together.

Fig. 5, is a sectional view taken on the line —5—5— of Fig. 1, showing its general construction.

Fig. 6, is a sectional view taken on the line —6—6— of the Fig. 10, showing means of attaching the walls together, at various points throughout the sections for preventing spreading of the bags.

Fig. 7, is also a sectional view taken on the line —7—7— of the Fig. 10, showing the construction of the back sections.

Fig. 8, is an enlarged detail of the ends of the side and front sections and the means for filling them with hot water.

Fig. 9, is a side view of the details shown in Fig. 8, showing the means for closing the section necks.

Fig. 10, is a plan view of my invention when unfolded in a flat member, showing the sections which it comprises, and means for attaching them together.

Fig. 11, is an alternate form of my device.

I will now describe more fully the detailed construction of my device, referring to the drawings and the marks thereon.

The vest preferably comprises four separate, flexible, hollow, water tight sections, 1, 2, 3 and 4, made of thin rubber sheets, or suitable waterproof material. The sections —1— and —2— forming the back portion of the vest, and the sections —3— and —4—, forming the front portion of the vest. The sections 1 and 3 being designed and placed symmetrically about a center line —A—A—, of Fig. 10, with the sections 2 and —4—. The outer edges —a— being shaped to form an elongated end —b— on each of the back sections —1— and —2—, while the upper ends of the sections —1— and —2— are formed with a circular notch —c— for fitting around the neck of the patient. The

combined width of the two back sections, at the top, being sufficient to extend across the back of the patient, and allow the extended parts —*e*— to fold over the shoulders. The elongated ends —*b*— of the sections —*1*— and —*2*— being of a length to allow same to be extended around the waist, and capable of completely encircling the body of the patient. The sections —*1*— and —*2*— are made of two very thin sheets of rubber, —*g*— and —*h*—, or suitable waterproof material, folded and attached at the edges and forming a hollow water tight enclosure therein. Both sections are provided with neck openings —*f*— at the extended ends —*b*—, and are fitted with a stopper —*5*— tightly screwed therein, providing means for filling each section with water as desired. The thin rubber sheets —*g*— and —*h*— are attached together at various points —*k*— by cementing small button sections tightly together, thus preventing the thin rubber walls from spreading when water is forced therein, and holding the sections as a thin compartment. The back sections —*1*— and —*2*— are attached together along the center line —*AA*— by the web —*6*—, which completely separates the two sections. At the upper ends of the shoulder parts —*e*— are attached web members —*7*— which are provided with button clips —*8*— fixedly attached thereto. Attached to the web members —*7*— and buttons —*8*— by the web strip —*10*— at the end are the front water sections —*3*— and —*4*—, each being made of two thin rubber sheets —*s*— and —*t*—, or suitable waterproof material, having their outer edges securely sealed, forming a water tight receptacle, and each provided with a neck —*m*— and stopper —*9*— tightly screwed therein. Like the sections —*1*— and —*2*—, the sheets —*s*— and —*t*— are attached together at various points —*k*—, by cementing small button sections together; also for preventing spreading of the rubber walls when filled with water. The outer edges of the sections —*3*— and —*4*— are provided with the curved walls —*w*—, of a shape and design to fit and engage the curved edges —*a*— of the back sections —*1*— and —*2*— when said back sections are folded around the patient's waist and the front sections —*3*— and —*4*— folded over the shoulders on the patient's chest, forming an approximately closed vest. Either section —*3*— or —*4*— may be detached from the back section by means of the clip buttons —*8*—. Web members —*11*— are attached to the inner edges of the front sections —*3*— and —*4*—, near the neck opening —*c*—, and are provided with small eyelets —*12*— for threading the tie cord —*13*— therein, and holding the sections close to the body of the user. Likewise each of the necks —*f*— and —*m*— are

provided with extended laps —*14*— and eyelets —*15*— for receiving the tie cord —*16*— therein, for securely fastening the jacket ends together. The four water sections when folded together, forming an approximately enclosing jacket for the shoulders and upper part of the body, all capable of being filled with hot water and completely surrounding the body thereby. The purpose of the button sections —*k*— being solely to prevent the thin walls from separating under pressure of the inclosed water, and the number required may vary with the size of the vest. Various modifications may also be made in the exact shape and contour of the water sections —*1*—, —*2*—, —*3*— and —*4*—, folding and fitting the body differently, at different desired points or places. It is also apparent that the front sections —*3*— and —*4*— may be joined together as one member by an intervening web similar to the web —*6*— as connecting the back sections —*1*— and —*2*—, forming the whole into a single blanket with a central neck hole —*c*— therein, the sections being folded and adjusted in the same manner as heretofore described.

The Fig. 11 also illustrates an alternate form of my device, designed approximately in a rectangular form, having a full circular opening provided through the center thereof, both ends folding down over the shoulders, front and back, in a manner similar to that heretofore described.

Having fully described my hot water vest, what I claim and desire to secure by Letters Patent is:

1. A water vest retainer adapted for fitting and inclosing the shoulders and upper portion of a human body for applying artificial temperatures, hot or cold, thereto, comprising two separated, flat front water receptacle sections, and two separated flat, back water receptacle sections, each formed with a separate neck opening therein and each section made of a double walled construction of flexible waterproof material and capable of retaining water therein throughout, means for inserting water in each of the front and back sections, said sections being so designed in their outer contour lines to fold over the shoulders and fit together along the side section edges for forming a complete vest inclosure, and means for connecting said sections together when folded.

2. A hot water vest adapted for applying artificial heat to the whole of the upper portion of a human body, simultaneously, comprising two separated, flat, L-shaped flexible back water retaining sections, and two separated, flat front flexible water retaining sections, all joined together by flexible web strips and provided with a centrally located neck opening, each of said sections being provided with a filling neck and stopper,

said sections being so designed to fold over the shoulders of a person and fit together along the section edges, forming a complete vest inclosure capable of completely inclosing the upper part of the body by water filled walls.

3. A water vest adapted for fitting and inclosing the shoulders and upper part of a human body for applying artificial temperatures thereto, comprising separated two L-shaped flexible back water retaining sections formed of double waterproof material, each sealed around their outer edges, each provided with a filling neck and stopper and joined together at their backs by a connecting web member, the straight portions of the sections being of a combined width to extend across the back of a person, and are provided with a neck opening therein, while the extended L-parts of the sections are of a length to encircle the body of the person

about the waist, said sections being capable of receiving water therein throughout the section, two separated flexible front water retaining sections, also made of double waterproof material cemented around their outer edges and provided with filling necks and stoppers, capable of receiving and retaining water therein throughout the sections, one of said front sections being joined to the top end of each of the back L-shaped sections and so shaped and designed when assembled as to form a full neck opening therein, and when the front sections are folded over the shoulders of the wearer they will fit and engage the edges of the L-shaped back sections encircling the waist, forming a complete vest inclosure thereby, and means for connecting the folded ends of the sections together.

In witness whereof I sign these specifications.

JOHN JIRASEK.
